DESIGN FOR A DRESS

Sylvia Faden, New York, N. Y.

Application January 27, 1941, Serial No. 98,450

Term of patent 3½ years

To all whom it may concern:

Be it known that I, Sylvia Faden, a citizen of the United States of America, residing in New York, county of New York, and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view thereof.

The characteristic feature of my design resides in the combination on the dress disclosed of the specific yoke which is tucked as shown in association with the particular floral embroidery and ornament at the lower edge of the yoke.

I claim:

The ornamental design for a dress, as shown and described.

SYLVIA FADEN.
